CLAIM

The ornamental design for a faucet escutcheon, as shown and described.

DESCRIPTION

FIG. 1 is a top, front, left-side perspective view of a faucet escutcheon showing my new design;
FIG. 2 is a top view thereof;
FIG. 3 is a front elevational view thereof;
FIG. 4 is a bottom view thereof;
FIG. 5 is a right side elevational view thereof, the left side being mirror symmetrical thereto; and,
FIG. 6 is a rear view thereof.
